WILLIAM J. HOFFMANN, OF BROOKLYN, NEW YORK

HEAT EXCHANGER

Application filed August 7, 1926. Serial No. 127,829.

This invention relates to an apparatus for and a method of heat exchanging, as well as for improvements in the design and construction of such apparatus.

- 5 The invention is particularly adaptable to heat exchangers in which are employed continuous carriers as, for example, cooling conveyors for commodities such as candies, confections, biscuits, cakes, etc. The invention 10 comprises a new and simple method of placing such a continuous carrier in direct contact with the heat exchanging devices and avoiding the use of separate pipes, tanks, pans, brine or other agencies. 15 The invention may be employed in heat exchanging mechanisms for either heating or cooling purposes, but I have in this specification described my invention as applied to refrigeration, although it may be readily 20 seen that it can be utilized for heating purposes.

One of the objects of this invention is to provide means so that the continuous carrier of material to be cooled is in constant contact 25 with refrigerating surfaces, which are prevented from sweating and from which are eliminated any condensation of moisture. The invention comprises a novel combination of cooling surfaces to which tubes or pipes 30 are intimately joined so as to increase the heat transmitting properties, and procure a maximum amount of refrigeration.

The invention further comprises means for reducing the cross-sectional area of the 35 cooling tunnel through which passes the conveyor, and thus cause the more rapid circulation of air and consequent cooling by convection. The material carried on the conveyors may be readily chilled without resorting to forced air circulation.

Another object is to provide a cooling surface which is entirely covered and yet separated from the adjoining heat exchangers by a heat insulating substance or air space.

45 The improved device presents means for cooling material rapidly and to a low temperature and in a limited amount of space. It is simple, practical and economical of construction.

50 In the drawings:

Fig. 1 is an elevation of a conveyor adapted to travel through a cooling tunnel.

Fig. 2 is a section along lines 2—2 of Fig. 1.

Fig. 3 is a section along lines 3—3 of Fig. 2.

Surmounting the packing table 1, Fig. 1, is 55 a conveyor 2, which passes through the cooling tunnel 3. The cooling tunnel 3 is provided with suitable air vents 4, as well as with pan 5 and drains 6.

In the tunnel 3 the conveyor 2 passes directly over the cooling surface or plate 7. Integral with the cooling plate are the heat exchanging tubes or pipes 8, which in a cooling mechanism carry a refrigerating agent, such as brine, ammonia, water, etc., and these 60 exchangers are welded, brazed or otherwise connected to the cooling surface 7, so as to increase the heat transmitting properties and extract therefrom a maximum amount of heat. The edges of the conveyor 2 are carried on non-metallic supports 9, which are 65 suitably spaced away from the cooling plate 7, so as to allow an air space 10 between the edges of the conveyor and the supports 9.

In the tunnel 3 are also provided laterally 75 placed temperature exchangers 11, which are suitably welded or brazed to the plates 12, and the plates 12 are so situated that there are air spaces 13 between the supports 9 and the bottom of plate 12. In this construction it will be 80 noticed that any splashing or moisture from the exchangers 11 will be deposited on the outside of plates 12 and drip down to pan 5 and be carried away by the drain 6. Should there, however, be any deposit of moisture on 85 the inside of plate 12, such moisture would fall down through the air space 13, and thus flow into the drain 6, similarly with the exchangers 8, and thus it will be seen that the elimination of any sweating is provided for, 90 and that such moisture be eliminated from the horizontal cooling surface 7.

The efficiency of the apparatus is further increased by the use of an internal area and volume reducing section 14, which may be 95 suitably placed in the tunnel 3. I have shown such a section in Fig. 2 as being held by projections 15 resting on the outer and upper part of the tunnel walls 16. This section may be of any convenient size and removable, if 100

so desired. Insertion of the section in tunnel 3 decreases the cross-sectional area and thereby causes a rapid circulation of air by convection and assists in chilling the material carried on the conveyor. If it is desired, 5 forced air circulation may be used, but I have found that by adjusting the side and location of the section 14 as well as the exchangers 11, I can eliminate the use of forced air circulation and procure satisfactory results. The 10 walls of the tunnel 3 may be insulated as at 17, so as to provide against loss of refrigeration.

The exchangers 11 are welded or brazed 15 as shown at 18, Fig. 3, along the sides of the plate 12, thus minimizing losses due to air spaces or pockets, and the lengths of such exchanger pipes connected by suitable means, such as joints 19. A similar construction is 20 employed in connection with the exchangers 8, as shown in Fig. 3.

It will be noticed that the material resting 25 upon the conveyor 2 is continuously being cooled by plate 7, and that such cooling is accentuated by the use of plates 12. This 30 degree of refrigeration can be increased by enlarging the cross-sectional area of the section 14, and decreased by lessening the same. The location of exchangers 11 in relation to 35 exchangers 8, as well as the size of the section 14, determine the rapidity of air circulation about the conveyor 2, and thus the degree of refrigeration may be altered as desired. The use of additional tanks, or pans, containing 40 water, brine and other refrigerating agents, as now commonly employed, is entirely eliminated.

It will be noted that, as shown in Fig. 2, 45 the horizontal cooling surface 7 is covered by the conveyor 2 and the horizontal cooling surface is separated from the adjoining sides by the heat insulating substance 9, as well as the air space 10, so that sweating of the 50 cooling surface 7 is eliminated.

It is understood that the foregoing description 55 of my invention, whilst explanatory, is not restrictive. It should be understood that departures may be made from the exact structures and arrangements therein shown and described without departing from the principles of the invention and without sacrificing its chief advantages, and I claim all the changes in the specification which legitimately come within the principles of my invention and the scope of my claims.

I claim:

1. In a heat exchanger the combination of 60 a carrier, lateral temperature changers, and a horizontal temperature changer over which the carrier passes, said horizontal temperature changer being separated from said lateral temperature changers.

2. In a heat exchanger the combination of 65 a carrier, lateral temperature changers and a horizontal temperature changer over which

the carrier passes, said horizontal temperature changer being separated from said lateral temperature changers, and means for causing a rapid air circulation and for limiting the space in which said air circulation takes place.

3. In a heat exchanger the combination of 70 a carrier, lateral temperature changers and a horizontal temperature changer over which the carrier passes, said horizontal temperature changer being separated from said lateral temperature changers, said temperature changers comprising plates separately constructed so as to permit moisture thereof to drip free of the carrier.

4. In a heat exchanger the combination of 75 a carrier, lateral temperature changers and a horizontal temperature changer over which the carrier passes, said horizontal temperature changer being separated from said lateral temperature changers, said temperature changers comprising plates separately constructed so as to permit moisture thereof to drip free of the carrier, and means for causing a rapid air circulation and limiting the space in which said air circulation takes place.

In witness whereof, I have signed my name to this specification this 5 day of August, 1926.

WILLIAM J. HOFFMANN.
